MAGAZINE MOUNTING FOR TYPO-
GRAPHICAL MACHINES

Le Roy W. Willis, Stamford, Conn., assignor to
Intertype Corporation, Brooklyn, N. Y., a cor-
poration of New York

Application June 28, 1934, Serial No. 732,897
In Germany August 15, 1933

10 Claims. (Cl. 199—46)

The present invention relates to improvements in typographical machines, and more especially to those of the general class disclosed in U. S. Letters Patent No. 436,532, granted September 16, 1890, wherein character bearing matrices are stored in a magazine or magazines mounted in the machine and from which the matrices may be delivered, under control of a keyboard, and assembled into lines from which type bars or slugs 10 are cast, after which the matrices are returned by distributing mechanism to their proper places of storage in the magazine or magazines.

In machines of this class as now generally constructed, one or a plurality of exchangeable magazines are employed, and the magazines may either be of full length, extending as a one-piece compartment from the distributor to the assembler entrance if they contain fonts of matrices for text composition in which a large number of like 15 character matrices are required or the magazines may be of the well known split construction comprising an upper matrix conducting section and a contiguous but separately exchangeable lower matrix containing section in the case of display composition in which a comparatively few like character matrices are required.

Such machines are usually provided with one-piece base frames, one to support each full length or split section magazine removably thereon, these frames being collectively arranged in superposed relation and are either tilttable rearwardly as a unit about an axis in the machine frame located substantially centrally with respect to the length of the magazine frames to permit exchanging of the magazine at the rear of the machine, or these frames are swingable, each separately about an axis or axes located at their upper ends, in fan-like manner to permit removal of the magazines at the front of the machine and over the assembler entrance. When split magazines are employed, it is advantageous to install them on any one of the superposed frames so that it is only necessary to exchange the lower magazine section in which the matrices are stored, when a different font is required. However, if it should be desired to install a full length magazine on a frame in place of a split magazine, the upper or conductor section of the split magazine must then also be removed. Machines of this class constructed for 40 rear removal of the magazines have the advantage that full length magazines as well as the upper sections of split magazines can be easily brought to an accessible position for removal merely by tilting the magazine supporting frames 50 rearwardly. In machines restricted to only front

removal of the magazines by fanning or spreading the one-piece frames apart about an upper axis to afford access to the lower section of a split magazine, the upper section of such magazine is located so high up in the machine that it is inaccessible and its removal can be accomplished only with difficulty. 5

The primary object of the present invention is to provide novel and improved means for mounting the magazines in the machine whereby all of the advantages of a machine constructed for rear removal of magazines will be retained, and at the same time, the magazines will be rendered removable from the front of the machine when such is desirable, it providing simplified and 10 improved means to provide free access for exchanging at the front of the machine, the lower or matrix containing section of a split magazine on one or another of a plurality of supporting frames. More particularly, the invention provides a magazine supporting frame of improved construction whereby, when split magazines are employed, less effort will be required of the operator in effecting magazine exchanges, either 15 of the lower section only of a split magazine or of 20 both the upper and lower sections of such a 25 magazine for substitution of a full length magazine. 30

In carrying out the invention, the magazine supporting frame, other than the lowermost one 35 which rests substantially centrally of its length on a pivot axis in the machine frame, comprises upper and lower sections of lengths corresponding substantially to the lengths of the sections of a split magazine, and these frame sections are 40 suitably held together, preferably by a hinged joint whose axis lies in the same plane with the abutting edges of the split magazine section and at or slightly above the plane of the top surface 45 of the magazine. 50

The present invention also provides mechanism operative to simultaneously tilt the set or plurality of magazine supporting frames and the magazines thereon about a pivotal axis in the machine located substantially centrally of the 45 length of these frames and to also swing a lower magazine frame section and the lower section of a split magazine thereon, upwardly about the axis connecting such lower frame section to the upper frame section. This arrangement has the advantage that since the weight of the entire 55 set of magazine supporting frames and the magazines thereon is balanced on a supporting axis located substantially centrally of their length, the effort required to tilt them 55

bodily upwardly at the front is much less than if they were supported and swung about axes at their rear ends. Furthermore, since a machine embodying the present invention affords the convenience of removal of full length magazines and the upper sections of split magazines at the rear of the machine, it is only necessary to provide access to and clearance for removal of the lower sections of split magazines at the front of the machine. Accordingly, the load to be lifted to provide the required clearance for front removal of magazine sections is confined to the lower split frame section and the lower magazine section thereon instead of the entire frame when made in one piece pivoted at the extreme upper end as heretofore.

To these and other ends, the invention consists in certain improvements and combinations and arrangements of parts all as will be herein-after more fully described, the features of novelty being pointed out particularly in the claims at the end of this specification.

In the accompanying drawing:

Fig. 1 is a side elevation of a typographical machine embodying means for mounting magazines therein in accordance with the present invention; and

Fig. 2 is a view similar to Fig. 1 but showing the magazine supporting frames and the magazines thereon in positions for exchanging the lower sections of split magazines at the front of the machine.

Similar parts are designated by the same reference characters in the different figures.

The invention is shown in the present instance as applied, for illustrative purposes, to a machine of the type familiarly known as a "Mixer" wherein the matrices may be assembled from either of two magazines at will and distributed simultaneously into both magazines. It is to be understood however that the invention is not restricted to machines of that type but is equally applicable to any other type of matrix composing and distributing machine, such for example as those having a plurality of magazines arranged in superposed relation and shiftable as a whole to bring one or another magazine in operative relation to single assembling and distributing devices, such adaptation of the invention involving merely simple mechanical changes within the scope of the invention.

In the present instance 1 represents a portion of the main stationary frame of a typographical machine of the well known class as shown generally in the patent hereinbefore referred to, 2 represents the entrance to the usual assembler which assembles the matrices delivered from the magazine or magazines into lines for the casting of type bars or slugs therefrom in the usual or well known manner, and 3 represents the distributor which returns the matrices in the usual manner to the magazine or magazines after disintegration of the matrix lines following the casting of the type bars or slugs therefrom.

According to the present invention, a main magazine supporting frame 4 is pivoted to rock or tilt into a forwardly or rearwardly inclined position by pivots 5 supported in the main frame 1, these pivots being located substantially centrally of the length of the frame 4. The frame 4 is provided on its upper side with cross rails 6 to removably receive and support the usual full length or one piece matrix magazine, or to removably receive and support the upper and lower sections 7 and 8 of a split magazine. The main

magazine supporting frame 4 also carries or supports above it a suitable number of upper and lower magazine supporting frame sections according to the number of magazines to be contained in the machine, a pair of upper and lower frame sections 9 and 10 being shown in the present instance. The upper frame section 9 is fixed to the frame 4 at a suitable height above it as by a bracket 11 at each side thereof, and the lower frame section 10 is joined to the upper frame section 9 preferably by a hinge embodying short pivot pins 12. The frame sections 9 and 10 are provided with cross ribs 13 and 14 on their upper sides to removably receive and support either an ordinary full length or one piece matrix magazine or the upper and lower sections 15 and 16 of a split magazine, as shown. The hinge pivots 12 which join the upper and lower frame sections 9 and 10 are located in the plane of the abutting ends of the magazine sections 15 and 16 at a level with or slightly above the top plates of these magazine sections, the portions 17 and 18 of the upper and lower magazine frames 9 and 10 which are joined by the pivot pins 12 being extended upwardly for this purpose, as shown.

Means is provided for lifting the lower frame section 10 to render accessible and facilitate removal of the underlying magazine section, and preferably for also tilting the frame 4 on its pivots 5 to bring the lower magazine into a position for removal at the front of the machine and over the assembler entrance 2, the frame section 10 and frame 4 being shown in such lifted positions in Figure 2 so that the lower magazine sections 8 and 16 may be readily removed forwardly over the assembler entrance. Such means comprises preferably a shaft 20 which extends transversely of and is mounted rotatably in the lower portion of the frame 4, this shaft 40 having a cam 21 fixed thereon and arranged to act on an extension 22 of the lower frame section 10 to swing the latter upwardly about the pivots 12 when the shaft 20 is rotated in the direction of the arrow, Fig. 1, by a handle 23 fixed on the shaft 20, the frame section 10 being thereby swung or lifted from the position shown in Fig. 1 to that shown in Fig. 2. The shaft 20 also has a cam 24 fixed thereon and arranged to bear on a surface 25 on the main stationary frame 1, so that as the shaft 20 is rotated from the position shown in Fig. 1 to that shown in Fig. 2, the frame 4 will be rocked about its pivots 5 in a direction to lift its forward end and the magazine section 8 thereon into the position shown in Fig. 2. The means thus provided serves to lift the frame section 10 and the magazine section 14 thereon above or in separated relation with the underlying magazine section 8 on the frame 4, thereby rendering the latter magazine section 60 readily accessible for removal or replacement, and simultaneously with or toward the completion of the upward swing of the frame section 10, the entire magazine supporting frame 4 is swung on its pivots 5 to raise the level of the bottom magazine section 8 so that it may be removed forwardly without obstruction by the assembler entrance 2. The location of the hinge pivots 12 is such that when the frame section 10 is swung upwardly, the upper magazine section 15 is not disturbed. Furthermore, by splitting the upper magazine frame into the sections 9 and 10 and hinging these sections on an axis which lies in the plane of the abutting ends of the magazine sections 15 and 16, the load to be 75

5 moved by the operator when turning the crank 23 is much less than would be the case if this frame were continuous from top to bottom and hinged to swing on an axis located at its upper end.

10 The above described construction enables the lower matrix containing sections of split magazines on one or another of the superposed frames to be readily exchanged without obstruction over the assembler front or entrance at the front of the machine, and obviously a full length magazine may be placed on one or another of the magazine frames, in place of the split magazine shown thereon, and such full length magazines 15 could be removed at the front of the machine. Removal of the upper magazine sections 7 and 15 may be readily accomplished by rocking the magazine supporting frames bodily or as a unit about the pivots 5, from their normal forwardly and 20 downwardly inclined position as shown in Fig. 1 to a rearwardly and downwardly inclined position, these upper magazine sections being thus brought into position for convenient removal at the rear of the machine, removal of the upper magazine 25 sections being necessary for example when the split magazines are to be replaced by full length magazines.

30 While the magazines are in their normal forwardly and downwardly inclined position in the machine, as shown in Fig. 1, their upper ends are positioned to receive matrices from the distributor 3 and their lower ends are positioned to deliver matrices to the assembler front or entrance 2. The magazines or the lower matrix containing 35 sections thereof are provided as usual with escapements 26 and 27 for controlling the delivery of matrices therefrom, and these escapements may be actuated by the reeds 28 and 29 forming part of the usual keyboard mechanism of the machine. 40 When the magazine frame 4 is rocked about its pivots 5 to raise or lower its forward end, the escapements 27 for the lower magazine or magazine section 8 will merely lift out of operative relation with and return to operative relation 45 with the respective controlling reeds 29 and in order to avoid interference of the reeds 28 with the tilting movements of the magazine frame 4 about its pivots 5, a set of auxiliary actuating levers 30 may be pivoted on the frame section 10 50 to cooperate with the escapements 26 of the magazine or magazine section thereon, these auxiliary levers extending forwardly into position for engagement by the upper ends of the reeds 28 which are located beyond the forward ends of the 55 magazines. The auxiliary escapement actuating levers 30 may be loosely pivoted on a rod 31 secured at its ends in the frame 10.

I claim as my invention:—

60 1. A typographical machine having a main frame, matrix assembling means and a magazine supporting frame comprising upper and lower contiguous sections constituting means for supporting upper and lower magazine sections and pivoted on the main frame substantially centrally of its length to tilt rearwardly for removal of the upper matrix magazine section therefrom, means for tilting the lower section of said frame to an extent sufficient to lift the lower magazine section thereon from operative relation with the 65 assembling means and to support it in a position for forward removal of such magazine section thereover.

70 2. In a typographical machine having a main frame, matrix assembling means supported thereon, and a main magazine supporting frame piv-

oted on the main frame on an axis located substantially centrally of the length of the main magazine supporting frame, an upper magazine supporting frame having a section thereof pivoted to swing vertically on said main magazine supporting frame, and means for swinging the forward end of the main magazine supporting frame and said section of the upper magazine supporting frame about their respective pivots and for supporting the same at positions for forward removal of magazines thereon over the matrix assembling means, and for separating the forward end of the magazine on the upper frame from that on the main magazine supporting frame.

15 3. In a typographical machine having a main frame, matrix assembling means supported thereon, and a main magazine supporting frame pivoted on the main frame on an axis located substantially centrally of the length of the main magazine supporting frame, an upper magazine supporting frame having an upper section rigidly secured to the main magazine supporting frame and a contiguous lower section pivoted to said upper section, and means on the main magazine supporting frame and cooperative with the upper magazine supporting frame thereon and with the main frame to lift the forward end of the main magazine supporting frame to bring a magazine thereon into position for removal over the matrix assembling means and to lift the forward end of the lower section of the upper magazine supporting frame relatively to the main magazine supporting frame.

20 4. In a typographical machine having a main frame and matrix assembling means thereon, superposed magazine supporting frames, one pivoted at its upper end to swing vertically relatively to the other magazine supporting frame and said magazine supporting frames being collectively pivoted on the main frame on an axis located substantially centrally of their length to tilt rearwardly for magazine removal, and means mounted on one of the magazine supporting frames and cooperative with the other magazine 25 supporting frame and with the main frame to relatively separate the forward ends of said magazine supporting frames vertically and to lift the forward end of the lower magazine supporting frame to bring a magazine thereon into position for removal forwardly over the matrix assembling means.

30 5. In a typographical machine having a main frame and matrix assembling means thereon, superposed magazine supporting frames, one comprising upper and lower sections respectively to carry upper and lower magazine sections thereon, said magazine supporting frames being collectively pivoted in the main frame to tilt rearwardly for rearward removal of upper 35 magazine sections therefrom, the lower section of the upper magazine supporting frame being hinged to the upper section of said frame, and means carried by the lower supporting frame and cooperative with the lower section of the upper supporting frame to swing said lower frame section vertically into position to remove the magazine section thereon over the assembling means and to separate the lower frame section 40 of the upper supporting frame from the lower supporting frame.

35 6. In a typographical machine having a main frame and matrix assembling means thereon, superposed magazine supporting frames pivoted on the main frame to tilt about an axis lo-

- cated substantially centrally of the length of said frames, split magazines each embodying upper and lower sections mounted removably on said magazine supporting frames, the upper magazine sections being removable rearwardly from their frames when the latter are tilted rearwardly, the upper magazine supporting frame embodying a lower section pivoted to swing upwardly about an axis located adjacent to its upper end to lift the lower magazine section thereon away from the lower magazine, and means for lifting said lower section of the upper magazine supporting frame and for lifting the lower end of the lower magazine supporting frame 10 to bring the magazine sections thereon into position for removal forwardly above the matrix assembling means.
7. A typographical machine having a main frame, matrix assembling means and a frame comprising upper and lower sections constituting means for supporting a magazine and pivoted on the main frame substantially centrally of its length to tilt rearwardly for removal of a matrix magazine therefrom, means for supporting the lower frame section for tilting movement in the main frame to an extent sufficient to lift a magazine thereon from operative relation with the assembling means, and means to support said lower section in a position for forward removal of such magazine over the assembling means.
8. In a typographical machine having a main frame, a matrix magazine comprising upper and

lower sections, a frame comprising corresponding contiguously disposed upper and lower sections hinged together for swinging one magazine section relatively to the other, and a common support on the main frame of the machine for simultaneously pivoting both of said frame sections for vertical swinging movement.

9. In a typographical machine having a main frame, a matrix magazine comprising upper and lower contiguous sections, a sectional frame for supporting each magazine section removably thereon, one independently of the other, the sections of said frame being hinged together, and means for supporting both sections of said sectional frame for simultaneous rearward swing- 10 ing movement in the main frame of the machine.

10. In a typographical machine having a main frame, a magazine comprising an upper matrix conducting section and a lower matrix containing section, and separate frames for supporting said magazine sections in a common plane for the passage of matrices through the upper section into the lower section, said separate frames being hinged together at a point corresponding to the adjacent ends of the upper and lower magazine 15 sections and above the level of the top of said sections, and means pivotally supporting said separate frames in the main frame of the machine on a common horizontal axis located below the level of said magazine sections.

LE ROY W. WILLIS.
